UNITED STATES PATENT OFFICE

122,901

DESIGN FOR A GAME BOARD

Melvin Marvin, Los Angeles, Calif.

Application June 17, 1940, Serial No. 93,055

Term of patent 14 years

To all whom it may concern:

Be it known that I, Melvin Marvin, a citizen of the United States, residing at 5835 South Main Street, Los Angeles, in the county of Los Angeles and State of California, have invented a new, original, and ornamental Design for a Game Board, of which the following is a specification, reference being had to the accompanying drawing, forming part thereof.

The figure is a plan view of a game board, showing my new design. This article is of no appreciable or substantial thickness.

I claim:

The ornamental design for a game board, as shown and described.

MELVIN MARVIN.
